UNITED STATES PATENT OFFICE

2,506,819

MECHANISM AND METHOD FOR INTRODUCING CONTENTS INTO CARTONS

Rudolph W. von Sydow, Middletown, Ohio, assignor to The Gardner Board and Carton Co., a corporation of Ohio

Application October 27, 1943, Serial No. 507,810

12 Claims. (Cl. 226—2)

1

My invention has to do with equipment for handling folding cartons, and in particular with means for introducing contents into erected cartons prior to closing the end thereof through which the contents are introduced. It was developed primarily for use in connection with a machine for setting up so-called click top cartons as described in the co-pending application of William A. Ringler, Walter E. Sooy and myself entitled Machine for forming reclosable cartons, Serial No. 482,806, filed April 12, 1943, now Patent Number 2,441,445, dated May 11, 1948.

This machine withdraws tubed cartons from a stack, erects them, positions them between blocks on a conveyer by which they are moved in a path adjacent various operating instrumentalities. Some of these instrumentalities spread the bottom flaps so that the contents may be introduced and later reclose and seal the bottom, the carton having at its bottom a seal end closure. Concurrently with these operations other instrumentalities fold and glue an openable and reclosable top for the carton.

My present invention does not have to do with operations upon the bottom or top closure elements of the carton, excepting the spreading of bottom closure flaps to permit introduction of the contents as will hereinafter appear; wherefore I do not herein describe the general aspects of the machine referred to. But my invention as herein set forth is not confined in its utility to that machine, nor to the specific carton described, nor to the introduction of contents into a carton at the bottom, being applicable to such introduction at either end. Rather it applies generally to the problem of introducing contents into cartons when the cartons are erected and moving along in a path wherein they are not necessarily horizontally oriented, but may be angularly or vertically disposed, and wherein the means for moving the cartons may be any suitable means for the purpose.

While the charges of contents fed into the cartons in the machine of the said patent are pre-packaged, or wrapped charges of smoking tobacco, the present invention is applicable to the introduction of unitary articles, assemblies of articles which can be handled as a unit, pre-formed block-like charges of material, and pre-wrapped or bagged materials, all as distinguished from loose, powdered, granular, or flaky bulk materials.

The principal object of my invention is the provision of a new and improved mechanism for introducing contents into cartons, which mecha-

2

nism is simpler than those heretofore devised, more positive in its operation, more accurate and less likely to get out of order.

It is an object of my invention to provide an apparatus wherein content charges or elements are rapidly introduced into cartons which are moving from a rotating holder for the charges.

It is an object of my invention to provide means for accurately locating the content charges 10 in the holding means, and hence with respect to the cartons as they move along. It is also my object to provide improved and greatly simplified means for spreading the end flaps of a carton to permit the introduction of its contents, in a 15 mechanism in which the direction of initial movement of the content charges with respect to the cartons, and the coaction of the holder with at least one of the flaps, combine to make certain that the flaps do not interfere with the introduction of the contents.

These and other objects of my invention which will be set forth hereinafter, or will be apparent to one skilled in the art upon reading these specifications, I accomplish by that certain arrangement of parts, and in that mode of operation of which I shall now describe an exemplary embodiment.

Reference is made to the drawings wherein:

Figure 1 is a plan view of the feed end of a 30 machine of the type hereinabove mentioned, and showing the features of my invention.

Figure 2 is a front elevational view of the same.

Figure 3 is a fragmentary cross-sectional view 35 taken on the line 3—3 of Figure 1, on an enlarged scale.

Figure 4 is a fragmentary cross-sectional view taken on line 4—4 of Figure 2.

Figure 5 is a fragmentary cross-sectional view 40 taken on line 5—5 of Figures 1 and 6.

Figure 6 is a cross-sectional view taken on the line 6—6 of Figure 5.

Figure 7 is a fragmentary cross-sectional view taken on line 7—7 of Figure 6.

Figure 8 is a fragmentary view similar to Figure 6 with the parts in an earlier position.

Referring to the figures, A is the top of a machine forming a table. At the feed end of the machine a stack of tubed and collapsed carton blanks, one of which is shown at 1, is placed in a hopper 2, whence by suitable mechanism 2a the cartons are withdrawn one by one, erected, i. e., squared up, then positioned between blocks 3 affixed to a chain or other conveyer mechanism 4. 55 Then the erected cartons are moved along a path

in the course of which they will be filled and closed. The particular mechanism for withdrawing the cartons from the stack, erecting them individually and positioning them between the blocks 3 of the moving conveyer 4, forms no limitation upon the present invention. This mechanism is more fully described and claimed in my co-pending application entitled Means for erecting and positioning cartons, Serial No. 507,811, filed October 27, 1943, now Patent Number 2,429,536, dated October 21, 1947.

On a sidewise extension of the machine table, indicated at A', I affix a stationary bushing or bearing member 5, in which a stub shaft 6 is rotatably mounted. To this shaft I affix a holding and transporting means for the content charges in the form of a star wheel 7. The wheel is notched at regular intervals as at 8, to accept the content charges; but the rear edge 9 of each notch (the wheel rotating clockwise in the direction of the arrow in Fig. 1), is made somewhat longer than the longitudinal dimension of the content charges. The other edge of the notch is shorter; but the intermediate portion of the wheel has an edge 10 which runs outwardly to meet the end of the longer notch edge as shown.

To the stub shaft 6, and as a means for driving it and the wheel 7, I affix a sprocket 11, which is driven by a chain 12, so that the wheel 7 turns in a timed relationship with the movement of the conveyer 4. The chain 12 may be driven in any way desired, or the stub shaft 6 may be otherwise driven. In Figure 2 I have shown the chain 12 running over a sprocket 13 on a vertical stub shaft 14, which carries a bevel gear 15. A flap folder 16 is affixed to the shaft 14, and the shaft is driven by a bevel gear 17 on a shaft 18, which in turn is driven by a chain 19 from the glue pot drive of the machine of the patent first hereinabove mentioned. This arrangement enables me to drive a content element kicker mechanism by means of the chain 12, as will hereinafter be described.

A vertically extending hopper 20, for the content charges 21, is affixed to the table A'. The sides and forward end of this hopper are raised sufficiently above the level of the table top to permit one of the content charges to be withdrawn sidewise therebeneath; and the wheel 7 is so positioned that it turns in the space between the table top and the lower ends of the side and forward walls of the hopper. Thus the wheel 7 acts as a means for withdrawing the content charges from the hopper. As the wheel turns beneath it, one of the content charges drops into one of the notches 8, and as the wheel turns further the leading edge 9 of the notch moves the content charge sidewise from beneath the stack, the intervening portion of the wheel meantime supporting the stack until the next content charge can drop into the next notch, and so on. As the content charges are moved arcuately by the wheel 7, they rest upon the table top.

It is necessary that the notches 8 be sufficiently oversize to permit the content charges to fall freely into the notches but it is also necessary that the content charges be accurately positioned with respect to the leading edge 9 of each notch. For this purpose I provide spring pressed fingers for urging the content charges against the edge 9. There is one of these fingers 22 for each notch of the wheel 7. The fingers are in the form of levers pivoted as at 23, beneath the wheel 7, and to the wheel; and at each pivot there is a spring 24 which urges the outer end of the finger against

its content charge. At the point where the content charges fall into the notches 8, from the hopper 20, it is necessary to get these fingers out of the way. To this end I affix a cam 25 to one side of the bearing 5 (Figure 2). The length and position of this cam are such that as the notched parts of the wheel 7 pass beneath the hopper 20, the fingers 22 are moved out of the way, as shown in Figure 2, but as soon as the wheel has moved a content charge from beneath the stack in the hopper, the finger is released by passing beyond the end of the cam 25, and it engages its content charge under gentle spring pressure, positioning the charge against the leading notch edge 9.

As the wheel 7 turns, charges are thus brought opposite the open ends of successive cartons on the conveyer 4. In the exemplary embodiment, the cartons have seal end flaps at their lower ends, which flaps extend generally in the planes of the side walls to which they are attached. It is necessary to move these flaps slightly out of the way, so that they will not interfere with the introduction of the content charges. The upper and lower seal end flaps, i. e., the flaps attached to the side walls of the cartons in the exemplary embodiment, are moved upwardly and downwardly respectively by a stationary sweep indicated at 26 in Figure 1. The trailing closure flap, i. e., the flap attached to the trailing end wall of the carton, will be bent slightly backwardly by dragging on an intermediate portion of this sweep. The leading closure flap may also be bent backwardly slightly; but it will be noted that the content charges move into position in an arcuate path so that should the leading closure flap be displaced backwardly, the content charge will be brought into position behind it and will tend to move it out of the way, as clearly shown in Figure 8. Thus the leading flap cannot interfere with the introduction of the content charge. Meanwhile, the point of the wheel 7 formed by the juncture of edge 9 with edge 10, will have turned into position ahead of the trailing sealing flap, thus insuring that this flap cannot interfere with the introduction of the content charge. The upper and lower side wall flaps having been given an outward set by the sweep 26, will maintain their positions; but they may be held outwardly by sweeps 25, if desired.

When a content charge, as at 21a, is thus positioned with respect to a carton, it is rapidly introduced into the body of the carton by the action of a kicker. This kicker is in the form of a lever 27, pivoted as at 28, on the table top. A vertical stub shaft 29 is also rotatably mounted in a bearing on the table top. It carries a sprocket 30, which meshes with chain 12 as shown. The shaft 29 also has affixed to it a double-ended cam lever 31, each end of which can actuate the kicker lever 27 in a clockwise direction. The forward end of the kicker lever is preferably provided with a cam follower in the form of pivoted roller 32. The kicker lever 27, as shown, lies beneath the wheel 7. It is urged in counterclockwise direction by a spring 33, and is preferably provided with a positioning stop 34, mounted on the table top, as will be clear from a consideration of Figure 7. When the lever rests against this stop its rear end lies toward the stub shaft 6, in a position to clear the content charges. The wheel 7 brings a content charge into position as at 21a, and opposite the end of the lever. At the moment this is accomplished, the cam means 31 rapidly moves the lever 27 in a clockwise direction; and the rear end of the

lever thus acts rapidly to kick the content charge 21a fully into the carton. The lever is then released by the cam 31, and the spring 33 brings it into position again to introduce the next content charge into the next carton.

The pressure of the spring fingers 22 on the content charge is a light spring pressure, not sufficient to interfere with the movement of the content charges as propelled by the lever 27; but I have shown how a counterpart for the cam 25 at 25a, may be positioned as to move the fingers 22 out of the way, at the time the kicking action takes place.

When the content charges have thus been introduced, the remaining operations on that end of the carton may be flap folding, glue applying, and pressing operations, forming no limitation upon my invention in its broadest aspect. It will be noted in Fig. 2, however, that a flap folding disk 16, notched as at 34a, may be employed to fold the rearmost sealing flap forwardly. This disk has a greater peripheral speed than the speed of travel of the cartons themselves on the conveyor 4. The remainder of the seal end flaps may be folded by stationary sweeps in a manner which will be readily understood. My content charge introducing mechanism, of course, is applicable to the introduction of content charges into cartons having other than seal end, end closures, or to the introduction of content charges into sleeves devoid of end closure means.

Modifications may be made in my invention without departing from the spirit of it.

Having thus described my invention, what I claim as new and desire to secure by Letters Patent is:

1. In a machine of the character described, in combination with a conveyor for moving erected carton bodies in spaced relationship, along a path, a hopper for content elements, a notched wheel turning beneath the hopper and acting to withdraw content elements, one by one, from the said hopper, means for driving the wheel in timed relationship with said first mentioned conveyor whereby the content elements are accurately positioned with respect to the open ends of said cartons, and means for propelling the content elements from the notches of said wheel into said cartons.

2. In a machine of the character described, in combination with a conveyor for moving erected carton bodies in spaced relationship, along a path, a hopper for content elements, a notched wheel turning beneath the hopper and acting to withdraw content elements, one by one, from the said hopper, means for driving the wheel in timed relationship with said first mentioned conveyor whereby the content elements are accurately positioned with respect to the open ends of said cartons, means for propelling the content elements from the notches of said wheel into said cartons, said last mentioned means comprising a pivoted lever having an end lying opposite a content element when in position for introduction, and driven means operating in timed sequence with the movements of said wheel for rocking said lever whereby to propel said content elements.

3. In a machine of the character described, in combination with a conveyor for moving erected carton bodies in spaced relationship, along a path, a hopper for content elements, a notched wheel turning beneath the hopper and acting to withdraw content elements, one by one, from the said hopper, means for driving the wheel in

timed relationship with said first mentioned conveyor whereby the content elements are accurately positioned with respect to the open ends of said cartons, means for propelling the content elements from the notches of said wheel into said cartons, said last mentioned means comprising a pivoted lever having an end lying opposite a content element when in position for introduction, driven means operating in timed sequence with the movements of said wheel for rocking said lever whereby to propel said content elements, and means for accurately positioning said content elements in the notches of said wheel, said means comprising positioning fingers pivoted to said wheel, resilient means for pressing said fingers against said content elements and means for moving said fingers out of the way at the time the notches of said wheel pick up said content elements from said hopper.

4. In a machine of the character described, in combination with a conveyor for moving erected carton bodies in spaced relationship, along a path, a hopper for content elements, a notched wheel turning beneath the hopper and acting to withdraw content elements, one by one, from the said hopper, means for driving the wheel in timed relationship with said first mentioned conveyor whereby the content elements are accurately positioned with respect to the open ends of said cartons, means for propelling the content elements from the notches of said wheel into said cartons, said last mentioned means comprising a pivoted lever having an end lying opposite a content element when in position for introduction, driven means operating in timed sequence with the movements of said wheel for rocking said lever whereby to propel said content elements, and means for accurately positioning said content elements in the notches of said wheel, said means comprising positioning fingers pivoted to said wheel, resilient means for pressing said fingers against said content elements and means for moving said fingers out of the way at the time the notches of said wheel pick up said content elements from said hopper, said last mentioned means comprising a fixed cam with respect to which said wheel rotates, said fingers being in the form of levers pivoted to said wheel, and having ends positioned to be engaged by said cam.

5. In a device for filling cartons with content elements, means for moving erected cartons along a path, said cartons having leading and trailing end closure flaps at the same end as so moved, means adjacent said carton-moving means for individually bringing content elements into a position for introduction into said moving cartons, said last mentioned content elements means comprising an endless conveyor disposed in an arcuate path lying in substantially the plane established by the movement of the leading and trailing end flaps of the carton as moved by said first-mentioned carton moving means, whereby said content elements are moved from a position at one side of said carton moving means in an arcuate path toward said carton moving means in timed relation therewith, said paths being substantially tangential to one another and the movement of said cartons and said content elements being in the same direction at the point of tangency, whereby to bring a leading corner of a content element into position behind a leading flap irrespective of a displaced position of said flap.

6. In a device for filling cartons with content

elements, means for moving erected cartons along a path, said cartons having leading and trailing end closure flaps at the same end as so moved, means adjacent said carton moving means and in substantially the plane established by the movement of said leading and trailing flaps for individually bringing content elements into a position for introduction into said moving cartons, said means acting to move said content elements from a position at one side of said carton moving means in an arcuate path toward said carton moving means in timed relation therewith, said paths being substantially tangential to one another and the movement of said cartons and said content elements being in the same direction at the point of tangency, whereby to bring a leading corner of a content element into position behind a leading flap irrespective of a displaced position of said flap, the means for bringing said content elements into position comprising a wheel notched to accept said content elements, the notched portions of said wheel having edges extending beyond the accepted content elements, said wheel having an edge cooperating with one of said last mentioned edges to engage trailing carton flaps and enforce a rearward position thereof.

7. In combination, a table top, a hopper, content elements in said hopper, a shaft journaled with respect to said table top, a wheel having a plurality of notches each of a size to accommodate a content element, said wheel being mounted on said shaft and adapted to turn beneath said hopper, conveyor means for moving erected cartons in a rectilinear path adjacent said wheel and in substantially the same plane therewith, said hopper being located on said table top to one side of said conveyor means, and timed means for turning said wheel, said shaft and said wheel being so located that said notches successively register with said hopper when said wheel is turned, content elements entering said notches by gravity when said notches register with said hopper, further turning of said wheel serving to withdraw said registered content elements from said hopper and position them with respect to said cartons for introduction therein at one point in the path of travel of said cartons.

8. In combination, a table top, a hopper, content elements in said hopper, a shaft journaled with respect to said table top, a wheel having a plurality of notches each of a size to accommodate a content element, said wheel being mounted on said shaft and adapted to turn beneath said hopper, conveyor means for moving erected cartons in a rectilinear path adjacent said wheel and in substantially the same plane therewith, said hopper being located on said table top to one side of said conveyor means, and timed means for turning said wheel, said shaft and said wheel being so located that said notches successively register with said hopper when said wheel is turned, content elements entering said notches by gravity when said notches register with said hopper, further turning of said wheel serving to withdraw said registered content elements from said hopper and position them with respect to said cartons for introduction therein at one point in the path of travel of said cartons and means operative at said point for propelling said content elements rapidly into said cartons.

9. In combination with means for moving erected cartons in spaced relationship in a path,

a stationary bearing mounted adjacent said path, a shaft rotatable in said stationary bearing, a wheel notched to accept content elements for said carton affixed to said shaft, pivoted, spring pressed locating means mounted on said wheel for locating said content elements by pressing them against sides of said notches, and a cam for operating said locating means mounted on said bearing.

10. In combination with means for moving erected cartons in spaced relationship in a path, a stationary bearing mounted adjacent said path, a shaft rotatable in said stationary bearing, a wheel notched to accept content elements for said cartons affixed to said shaft, pivoted, spring pressed locating means mounted on said wheel for locating said content elements by pressing them against the sides of said notches, a cam for operating said locating means mounted on said bearing, and means for driving said shaft in synchronism with the means for moving said cartons whereby content elements located in the notches of said wheel are brought into position behind leading flaps of said cartons, said wheel having portions for insuring a backward position of trailing flaps of said cartons.

11. A process of introducing content elements into cartons which comprises moving erected cartons in spaced relationship along a rectilinear path, moving content charges in spaced relationship adjacent said path in an arcuate path and in timed relationship to the movements of said cartons, bringing leading corners of said content elements behind leading flaps of said cartons, propelling said content elements rapidly into said cartons when positioned with respect thereto, and enforcing a backward position of trailing flaps of said carton while so propelling said content elements.

12. In combination, means for moving erected cartons in spaced relationship in a rectilinear path, rotary notched means for bringing content elements into position for insertion in said cartons, stationary means for moving outwardly a pair of opposite flaps of said cartons and a trailing flap thereof, the rotary positioning means being driven in timed relation to said carton moving means, and acting to bring content elements behind a leading flap of said cartons, means for propelling said content elements into said cartons, and means thereafter operating in timed sequence with said rotary means for folding said rearward flap forwardly.
